(57) **CLAIM**

The ornamental design for an electric bicycle, as shown and described.

DESCRIPTION

FIG. 1 is a top, rear, and left side perspective view of an electric bicycle embodying my new design;

FIG. 2 is a bottom, front, and right side perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is an enlarged and partial perspective view of area 9 in FIG. 1; and,

FIG. 10 is an enlarged and partial perspective view of area 10 in FIG. 1.

The broken lines shown in the drawings are included for the purpose of illustrating portions of the electric bicycle that form no part of the claimed design.

1 Claim, 10 Drawing Sheets
